CLAIM

The ornamental design for a surge protector, as shown and described.

DESCRIPTION

FIG. 1 is a right, front perspective view of the surge protector, showing my new design;

FIG. 2 is a front view thereof;

FIG. 3 is a rear view thereof;

FIG. 4 is left side elevational view thereof;

FIG. 5 is a right side elevational view thereof;

FIG. 6 is a top plan view thereof; and,

FIG. 7 is a bottom plan view thereof.

In the drawings, the broken lines are for the purpose of illustrating portions of the surge protector that form no part of the claimed design.

1 Claim, 6 Drawing Sheets
